Primary Examiner — Clare E Heflin(74) *Attorney, Agent, or Firm* — Nixon & Vanderhye, P.C.(57) **CLAIM**

The ornamental design for a “luminaire,” as shown and described.

DESCRIPTION

FIG. 1 is a perspective view of a luminaire in accordance with our new design;

FIG. 2 is a front elevation view thereof, the rear elevation view being a mirror image thereof;

FIG. 3 is top plan view thereof;

FIG. 4 is a bottom plan view thereof;

FIG. 5 is a right-side elevation view thereof, the left side elevation view being a mirror image thereof;

FIG. 6 is a reference view showing the luminaire in a first exemplary state of use; and,

FIG. 7 is a reference view showing the luminaire in a second exemplary state of use.

Subject matter shown in dashed lines is for environmental purposes only and forms no part of the claimed invention.
